COMBINATION FEED SIZER AND CUTTER

John L. Selman, El Paso, Tex.

Application June 20, 1936, Serial No. 86,369

6 Claims. (Cl. 107—8)

My invention has relation to machines for reducing in size any character of feed material, including the by-products of cotton-seed, such as meal and cake, and for forming these and other products into small particles such as cubes or the like.

One of the principal objects of my invention is in forming these products into cubes to exclude excessive moisture from the cubes made from finely ground cake, as such moisture causes the cubes to sour and become worthless for feeding purposes. The machine is hence so constructed that these cubes are compressed in their formation and the excess moisture eliminated.

Another object of my invention is the provision in its construction for causing the material to be fed into the machine at both ends thereof where it is drawn to a common collecting point, thrown out by centrifugal force of the machine into a cylinder die and thence operated upon by cutting rollers as it is formed into the cubes.

With the foregoing and other important objects in view, my invention will be clearly understood from a perusal of the following detailed description, taken in connection with the accompanying drawing, and in the drawing:

Figure 1 is a side elevational view of the machine;

Figure 2 is an enlarged detail sectional view with parts broken away;

Figure 3 is a transverse vertical sectional view of Figure 2, taken on the line 3—3 thereof;

Figure 4 is an end elevational view of one of the roller cutters; and

Figure 5 is a perspective view of two of the characteristic forms of the product of the machine.

Referring now in detail to the drawing, the machine has a framework comprising the supporting base 1 to which are bolted, welded, or otherwise secured thereto the legs or supports 2 and 3.

The machine is constructed in such a manner as to enable the feed to be introduced at each end thereof and therefore there are provided two hoppers 3a, and the material is thus carried to the center by the conveyors and delivered to the cylinder die, indicated generally at 6. Thus the conveyor blades 4 are carried on shaft 7, while the conveyor blades 5 are carried on the shaft 8. Similarly the blades 4 have a spiral movement from right to left, while the blades 5 move in a direction left to right, as will be clearly understood by reference to Figure 2.

In the lower part of the framework supports 2

and 3 is a main drive shaft 9 with a drive pulley 11 to which power may be applied for driving the machine. A pulley 12 mounted on main shaft 9 and a pulley 13 mounted on the shaft 7 in connection with a belt 14 rotates the shaft 7. The shaft 8 also carries a pulley 15, connecting this pulley with a pulley 16 on the main drive shaft 9 by means of the belt 17.

Rotatably mounted in the inner side of each of the hoppers 3a is a hollow shaft 18 and this hollow shaft provides a lining for the conveyor blades and through which the blades rotate in conveying the material into the cylinder die. To provide a more positive feeding effect of the material this hollow shaft 18 is made to rotate in an opposite direction to that of the shafts 7 and 8—that is, while the latter shafts rotate to the right in the customary manner, the hollow shaft 18 rotates to the left. This is accomplished by the pulleys 20 and 21 in connection with the crossed belt 22, and at the opposite side of the machine by the pulleys 23 and 24 and crossed belt 25. Shaft 18 has bearings 26 and 27 with oil cups 28 and 29.

The hollow shaft 18, as will be seen from Figures 2 and 3, has several elongated slots 30 at the point where this shaft passes through the cylinder die, for the purpose of permitting the material to be thrown out from the shaft into the die. A bar 30 holds the hoppers 3a in position and in alignment with the shaft 18, this bar being bolted to the supports 2 and 3 as will be apparent from Figure 1.

As the material is fed into the machine at each end the conveyors deposit it in a cylinder die through the said slots 30a, where it is acted upon by the roller cutter shown in detail in Figure 3. The cylinder die is composed of the two hubs 31 with an opening for seating the hubs on the hollow shaft 18 and each hub includes an annular flange 32. Between these flanges and bolted as at 33a or otherwise secured thereto is the cylinder 33 of the cylinder die. This die is constructed of steel and is provided with spaced openings through its walls, as clearly shown in Figures 2 and 3. These openings are tapered outwardly from the inside of the cylinder as shown at 34 to about midway of the thickness of the die or cylinder wall and then the diameter is uniform to its delivery end 35. In this manner the material is compressed when it enters the tapered entrance and further compressed as it reaches the uniform bore or delivery end of the opening. This is my preferred form of opening or aperture, although any character of outlet may

be placed or drilled in the die wall as preferred. This cylinder die is rotated in the same direction (to the right) as the shafts 7 and 8, by means of the two sprocket gears 36 and 37 and chains 38 and 39, as will be clear from Figures 1 and 2.

As the material is thrown by centrifugal force from the slotted portion of the hollow shaft 18 it is acted upon by the roller cutters previously referred to. One of these cutters is shown per se at Figure 4 and consists of the roller body 40 with an opening 41 whereby each roller cutter is rotatably mounted upon a shaft 42, each shaft being carried on a spider 43, the latter mounted on and rotating with the hollow shaft 18. The peripheries of these roller cutters are formed into the sharp, chilled steel knives 44, and thus cut the material and at the same time force it into the apertures, where it is forced out into the cubes 45 as illustrated in Figure 5.

In the operation of the machine, the material is fed into the hoppers 3a at each end, conveyed by the conveyor blades into the slotted openings 30a in the hollow shaft 18, where the centrifugal force of the machine throws the feedstuff out into the cylinder die. Here the knives 44, rotating around the inner peripheral wall of the cylinder, cut the material and at the same time force it through the openings in the cylinder die, thus compressing the feed and forcing out excessive moisture therefrom. As the material is forced out a striker bar (not shown) cuts or breaks off the exuding material and it is thus made into the cube forms 45.

It is believed the foregoing explanation is sufficient without further description. My invention is not to be understood as limited to the precise construction here shown and described, as modifications and alterations may be made therein which will be within the intent and purpose thereof and as covered in the claims appended hereto.

What I claim as new is:

1. A machine of the character described, comprising a framework supporting an elongated hollow member with conveyors rotatably mounted therein and communicating with a hopper at each end of the machine; means providing a common point of collection for the material thus conveyed inwardly, said means constituting a cylinder die with apertures formed therein, and cutting means carried in said cylinder whereby the material is cut and simultaneously forced through said apertures and delivered from the machine into cubes or the like.

2. A machine of the character described comprising a framework supporting a revoluble hollow member, hoppers communicating therewith at each end thereof, separate conveyor means rotatably mounted within said hollow member, means for rotating said hollow member in one direction, means for rotating the conveyor means in an opposite direction, and including a cylinder die mounted on and rotatable on said hollow member.

3. A machine of the character described, comprising a conveyor shaft in two sections, a hollow rotatable shaft in which the two sections are rotatably mounted, hoppers at each end of the hollow shaft and opening therein, conveyor blades carried by each section of the conveyor shaft, one blade having a right-hand flight directional turning movement, and the other blade a left-hand flight directional turning movement, to convey the material to the center of the machine, including a cylinder with spaced apertures and means for simultaneously cutting, compressing and forcing the same through said apertures.

4. A machine of the character described, and as set out in claim 3, said cutting means comprising rollers with knives on their peripheries and carried by a spider form, said knives and rollers adapted to travel around and on the inner periphery of said cylinder.

5. A machine of the character described, and as defined in claim 3, said hollow shaft having slotted elongated openings at a point adjacent the inner ends of said sectional shaft to permit the material carried inwardly from each end of the machine to be thrown out centrifugally by the rotation of the hollow shaft.

6. A machine of the character described, comprising a framework, a hollow shaft rotatably mounted in the framework, with hoppers at each end thereof, a conveyor shaft in two parts, each part carrying blades whereby each blade conveys the material in a direction inwardly from each end of the machine to a common collection point of the material, means for rotating the hollow shaft, means for rotating the conveyor shafts; and including a cylinder die disposed centrally of the machine, said die comprising side plates with means for loosely mounting the plates on said hollow shaft, and a die plate with spaced apertures to complete the cylinder, said hollow shaft and conveyor shafts rotating in opposite directions, said cylinder die rotating in the same direction as the conveyor shafts.
